UNITED STATES PATENT OFFICE.

WARD MELVILLE, OF OLD FIELD, AND RICHARD H. SMYTHE, OF BROOKLYN, NEW YORK, ASSIGNORS TO MELVILLE SHOE CORPORATION, A CORPORATION OF NEW YORK.

DESIGN FOR A STORE FRONT.

Application filed June 19, 1928. Serial No. 27,201. Term of patent 14 years.

To all whom it may concern:

Be it known that we, WARD MELVILLE and RICHARD H. SMYTHE, citizens of the United States, residing, respectively, at Old Field, county of Suffolk, State of New York, and Brooklyn, Kings County, State of New York, have invented a new, original, and ornamental Design for Store Front, of which the following is a specification, reference being had to the accompanying drawing, forming a part hereof.

In the drawings,

Fig. 2 is a section view of the same taken on the lines 2—2 of Figure 1.

We claim:

The ornamental design for a store front, as shown.

WARD MELVILLE.
RICHARD H. SMYTHE.
